POCKET LIGHTER

Louis Lefant, Paris, France, assignor to Cartier,
Societe Anonyme, Paris, France, a company
of France

Application February 18, 1933, Serial No. 657,374
In France May 14, 1932

9 Claims. (Cl. 67—7.1)

When it is desired to reduce the space occupied by pocket lighters, some difficulties are met with for suitably disposing the organs and especially those that serve to the adjustment of the flint, especially if the lighter is of the type including a hinged lid and a spark wheel fitted with a milled wheel rotating about a vertical axis, this arrangement being however the most advantageous for readily operating the lighter.

5 The object of the present invention is to provide a lighter that fully solves that problem since it occupies but a little space while permitting an efficient and accurate adjustment of the flint.

10 The essential feature of the lighter according to my invention lies in the fact that the spring that pushes the flint against the spark wheel is not disposed horizontally as in known lighters but vertically, that is to say in a direction parallel to the head of the lighter. Said spring acts on the flint through a pivoting bell crank lever.

15 According to another important feature of my invention, a removable reservoir is fitted inside the casing of the lighter, said reservoir being intended to receive the supply of fuel, and being provided with one or several capillary orifices which permits a continuous flow of said fuel from said reservoir to the wick. According to an embodiment of my invention said capillary orifice may consist of a slight clearance provided in the thread of the screw that closes the opening through which the reservoir is filled. Said orifice might also consist of a groove.

20 A preferred embodiment of my invention will be hereinafter described with reference to the accompanying drawing, given merely by way of example, and in which:

25 Fig. 1 is a vertical section of the lighter according to my invention on the line 1—1 of Fig. 2;

30 Fig. 2 is a plan view of said lighter, the lid thereof being opened;

35 Fig. 3 is a vertical sectional view of the lighter on the line 3—3 of Fig. 2;

40 Fig. 4 is a part sectional view on the line 4—4 of Fig. 1;

45 Fig. 5 is a sectional view of the fuel reservoir removed from the lighter;

50 Fig. 6 is a plan view of said reservoir thus removed from the lighter;

55 Figs. 7 and 8 are perspective views of the lighter with its lid closed, and its lid open respectively.

The lighter shown in the accompanying drawing comprises an elongated prismatic casing 1,

closed at its upper part by a lid 2, hinged at 3 on said casing. On casing 1 and under the lid thereof, there is fixed the horizontal plate 5 supporting the tube 6 that is intended to receive the wick. Said plate also supports a 5 vertical spindle 7 on which are mounted milled wheel 8 and spark wheel 9. Finally, supporting member 10 including a horizontal guide 11 for flint 12 is also provided on said plate 5.

Inside said supporting member 1 is disposed a 10 lever 13 pivoted about a pin 14 fixed on said supporting member, the end 13^a of said lever 13 bearing against flint 12. Said lever 13 is also provided with a lug 13^b adapted to co-act with a sloping surface 15 of a vertical rod 16 guided 15 inside supporting member 10. Said rod 16 is provided with a shoulder 17 against which is applied the end of a spiral spring 18 which is compressed in a vertical tube 19 fixed to the casing of the lighter. Said spring is held in 20 position by a screw 20 which is screwed into the lower part of tube 19, and which permits by suitably screwing or unscrewing it, to modify the tension of 18.

It should be understood that under the action 25 of said spring, rod 16 is pushed upwardly and tends through its inclined surface 15 to cause lever 13 to pivot in the direction of arrow F, in such manner as to apply end 13^a of said lever against flint 12 and to produce a good contact 30 of said flint and spark wheel 9. The lever 13 thus constitutes a bell crank lever, the work arm 13^a of which engages and bears against the flint 12 and the power arm 13^b of which is engaged and actuated by the inclined camming 35 surface 15 of the spring actuated rod 16. Lever 13 is so devised that the strength of spring 18, transmitted through the crank bell, may produce a substantially uniform pressure on the flint whatever the state of wear and tear of 40 said flint may be. The ratio of lever arm 13^b to lever arm 13^a and the shape of the levers and of sloping surface 15 are suitably calculated for this purpose. The adjustment of the compressing strength of spring 18 is made once and 45 for all by means of screw 20. Adjacent to tube 19, I provide inside the casing a second tube 21 which receives a small leaf spring 22, the further end 23 of which bears against a small lever 24 integral with the lid. Said spring 22 serves 50 to open said lid, the displacement of which is limited by hinged stops 2^a.

The lower part of casing 1 is open so as to permit introducing therewith a small reservoir 4, intended to contain the supply of fuel. Said 55

reservoir 4 is stopped by screw 25, and I provide either a slight clearance space between the threads of said screw and those of the opening for said screw, or one or several lateral grooves 26, so as to create capillary ducts through which the fuel flows to a pad of cotton 27, which surrounds the lower end of the wick. Said reservoir is given a particular shape which can be seen in Fig. 3, so as to fit on tubes 19 and 20 containing springs 18 and 22 respectively, disposed inside the casing.

The fact that spring 18 that serves to apply the flint against the spark wheel is disposed in the casing of the lighter, clears the upper part 15 of said lighter and makes it possible to utilize a hinged lid such as 2, and not merely a cap not connected with the casing as in some known lighters. Said lid is of a special cutaway shape as shown in Figs. 7 and 8. It forms the three 20 faces of a cube to wit faces a, b, c shown in solid lines in Fig. 8. Two of the faces of the cube that are missing from the lid, to wit faces d and e shown in dotted lines in Fig. 8 are provided on the casing of the lighter at d¹ and e¹. They form a kind of guard permitting no contact of the fingers with the spark wheel and the wick holder, slot 8^a however being provided in said faces for allowing the milled edge of wheel 8 to project from the casing.

30 The fact that face d of the cube is not present on the lid further creates in said lid a notch which in the open position thereof makes it possible to easily reach guide 12 in order to replace the flint.

35 Finally, face a of the lid carries cap 6^a intended to cover the wick carrying tube when said lid is closed in order to prevent the wick becoming clogged by being impregnated with combustible matter. The wick is ventilated whenever the lid is opened owing to the provision of notch c¹ of the casing corresponding to face c of the lid.

While I have disclosed in the above description what I deem to be a preferred embodiment 45 of my invention, it should be well understood that I do not wish to be limited thereto, as there might be changes made in the arrangement, disposition and form of the parts without departing from the principle of my invention as 50 comprehended within the scope of the appended claims.

What I claim is:

1. A pocket lighter of the type described comprising in combination, a vertical casing, a horizontal plate at the top of said casing, a vertical spindle carried by said plate, a spark wheel mounted on said spindle, a milled operating wheel also mounted on said spindle and operatively connected with said spark wheel, a flint, 55 guiding means carried by said plate for holding said flint in a horizontal position juxtaposed with said spark wheel, a spiral spring vertically mounted in said casing, a stop for the lower end of said spiral spring, a sliding rod vertically 60 guided in said casing and resting upon the upper end of said spring, a sloping surface at the upper end of said rod, and a bell crank journaled in said casing above said plate having one arm in contact with said sloping surface and the other 65 arm in contact with said flint so as to hold it firmly against said spark wheel.

2. A pocket lighter embodying a spark wheel mounted for rotation, means for rotating said wheel, a flint, a flint guide for holding the flint 70 in juxtaposed relation to the spark wheel, a bell

crank lever mounted with its work arm in co-operative relation to the flint, and a spring pressed slide having an inclined camming surface bearing against the power arm of said lever to force its work arm against the flint for the purpose of holding said flint in firm frictional contact with the spark wheel.

3. A pocket lighter embodying a spark wheel mounted for rotation, means for rotating said wheel, a flint, a flint guide for holding the flint 10 in juxtaposed relation to the spark wheel, a bell crank lever mounted with its work arm in co-operative relation to the flint, and a spring pressed slide having an inclined camming surface bearing against the power arm of said lever 15 to force its work arm against the flint for the purpose of holding said flint in firm frictional contact with the spark wheel, said inclined camming surface of the spring pressed slide being shaped to automatically compensate for wearing away of the flint whereby a substantially 20 uniform frictional relation exists between the spark wheel and the flint throughout the life of the latter.

4. A pocket lighter embodying a spark wheel 25 mounted for rotation, means for rotating said wheel, a flint, a flint guide for holding the flint in a position to extend substantially radially from one side of the spark wheel, a bell crank lever positioned with its work arm bearing 30 against the outer end of said flint, a plunger mounted for sliding movement in a direction parallel to the axis of the spark wheel and provided with an inclined camming surface bearing against the power arm of said bell crank 35 lever, a coil spring arranged with its axis parallel to the axis of the spark wheel and bearing against the plunger to force the inclined surface of the latter against the power arm of the lever, and thereby force the work arm of the 40 lever against the flint to hold said flint in firm frictional contact with the spark wheel, and means for placing said spring under the desired tension.

5. A pocket lighter comprising a casing provided near one end with an end plate and having a cover hinged to said casing along one of the sides of said plate, the walls of said casing extending above said plate along the side thereof opposite to the hinge and one of the adjacent 50 sides, the lateral sides of the cover being complementally cut away to correspond in shape to the walls of the casing, said cover being foldable into closed position to form between the cover and the said end plate a closed compartment, and sparking means housed within said compartment.

6. A pocket lighter comprising a casing provided near one end with an end plate and having a cover hinged to said casing along one of the sides of said plate, the walls of said casing extending above said plate along the side thereof opposite to the hinge and one of the adjacent sides, the lateral sides of the cover being complementally cut away to correspond in shape to the walls of the casing, said cover being foldable into closed position to form between the cover and the said end plate a closed compartment, sparking means housed within said compartment, and elastic 65 means tending to open the cover.

7. A pocket lighter which comprises in combination, a vertical casing, a plate at the top of said casing, a spark wheel mounted on said plate for rotation on an axis perpendicular 75

thereto, means for rotating said wheel, a flint, a flint guide carried by said plate for holding said flint to extend substantially radially from one side of said spark wheel and in substantially parallel relation with said plate, a spiral spring mounted in said casing with its axis in parallel relation to the height of said casing, said spring extending under said plate, a stop for the lower end of said spring carried by said casing, and means for operatively connecting the upper end of said spring with said flint so as to keep said flint in firm frictional contact with said spark wheel.

8. A pocket lighter which comprises in combination, a vertical casing, a plate at the top of said casing, a spark wheel mounted on said plate for rotation on an axis perpendicular thereto, a milled wheel coaxial with and operatively connected to said spark wheel for imparting rotation to the latter, a flint, a flint guide carried by said plate for holding said flint to extend substantially radially from one side of said spark wheel and in substantially parallel relation with said plate, a spiral spring mounted in said casing under said plate in substantially vertical position, a stop for the lower end of said spring carried by said casing, and means for operatively connecting the upper end of said spring with said flint so as to keep said flint in firm functional contact with said spark wheel.

25

lower end of said spring carried by said casing, and means for operatively connecting the upper end of said spring with said flint so as to keep said flint in firm functional contact with said spark wheel.

9. A pocket lighter which comprises in combination, a vertical casing, a plate at the top of said casing, a spindle carried by said plate at right angles thereto, a spark wheel mounted on said spindle, a milled operating wheel also mounted on said spindle under said spark wheel and operatively connected to said spark wheel for imparting rotation thereto, a flint, a flint guide carried by said plate for holding said flint to extend substantially radially from one side of said spark wheel and in substantially parallel relation with said plate, a spiral spring mounted in said casing under said plate in substantially vertical position, a stop for the lower end of said spring carried by said casing, and means for operatively connecting the upper end of said spring with said flint so as to keep said flint in firm functional contact with said spark wheel.
